FIG. 2

FIG. 1

FIG. 1 is a side elevational view of a bollard light fixture showing my new design, and this is substantially the side elevational view of this light fixture from any side; and

FIG. 2 is a top plan view of the light fixture shown in FIG. 1.

The top section is substantially a hemispherical shell of light transmitting material, and the middle and bottom sections of this fixture are of substantially opaque material.

The lamps are shown in broken lines for illustrative purposes only. The top hemisphere in FIG. 1 is fragmentarily shown for purposes of disclosure; the bollard in FIG. 1 is broken away to indicate indeterminate length.

I claim:

The ornamental design for a bollard light fixture, substantially as shown and described.
